UNITED STATES PATENT OFFICE

BENJAMIN GROSS, OF NEW YORK, N. Y.

DESIGN FOR A FINGER RING OR ARTICLE OF SIMILAR NATURE

Application filed April 9, 1930. Serial No. 35,202. Term of patent 7 years.

all whom it may concern:

Be it known that I, BENJAMIN GROSS, a citizen of the United States, residing in New York city, in the county of New York, and State of New York, have invented a new, original, and ornamental Design for a Finger Ring or Article of Similar Nature, of which the following is a specification; reference being had to the accompanying drawing forming a part thereof.

Figure 1 is a perspective view of a finger ring showing my new design.

Fig. 2 is a developed edge view of that portion of the ring from A—B, Fig. 1.

The portion of Fig. 2 between C and D represents the remainder of the ring excluding that portion from A to B in Fig. 1.

I claim:

The ornamental design for a finger ring, or article of similar nature, as shown and described.

In testimony whereof I affix my signature.

BENJAMIN GROSS.
